UNITED STATES PATENT OFFICE

169,836

TIRE

William F. Billingsley, Silver Lake, Ohio, assignor
to The B. F. Goodrich Company, New York,
N. Y., a corporation of New York

Application December 19, 1952, Serial No. 22,791

Term of patent 14 years

(Cl. D90—20)

To all whom it may concern:

Be it known that I, William F. Billingsley, a citizen of the United States of America, residing at Silver Lake, in the county of Summit and State of Ohio, have invented a new, original, and ornamental Design for a Tire, of which the following is a specification, reference being had to the accompanying drawing, forming a part thereof.

In the drawing:

Fig. 1 is a perspective view of a tire showing my new design, it being understood that the design of the segment shown in full lines is repeated about the entire side wall.

Fig. 2 is a partial side view of the sidewall design.

Fig. 3 is a section through the tire taken on line 3—3 of Fig. 2.

The dominant features of my design reside in those portions shown in full lines.

I claim:

The ornamental design for a tire, as shown and described.

WILLIAM F. BILLINGSLEY.
